Primary Examiner — Derrick Holland*Assistant Examiner* — Lauren Calve(74) *Attorney, Agent, or Firm* — Leason Ellis LLP(57) **CLAIM**

The ornamental design for a shirt and tie arranged in a box, as shown and described.

DESCRIPTION

FIG. 1 is a front elevation view of a shirt and tie arranged in a box showing my new design according to a first embodiment; FIG. 2 is a bottom plan view thereof; FIG. 3 is a top plan view thereof; FIG. 4 is a rear elevation view thereof; FIG. 5 is a front elevation view of a shirt and tie arranged in a box showing my new design according to a second embodiment;

FIG. 6 is a bottom plan view thereof;

FIG. 7 is a top plan view thereof; and,

FIG. 8 is a rear elevation view thereof.

The broken lines shown in FIGS. 1-8 represent unclaimed subject matter and form no part of the claimed design.
